UNITED STATES PATENT OFFICE

CHARLES S. CARD, OF CORTLAND, NEW YORK, ASSIGNOR TO THE BREWER-TITCHENER CORPORATION, OF CORTLAND, NEW YORK, A CORPORATION OF NEW YORK

METHOD FOR FORGING INSULATOR CAPS

Application filed May 12, 1930. Serial No. 451,581.

This invention relates to the art of hollowed metal forgings and more particularly to the production of a one-piece cap or bell-shaped socket adapted to securely mount 5 therein the neck of an insulator disk of the multiple suspension type as used in connection with high-tension electric transmission lines or the like. My invention in certain particulars represents a refinement in method 10 of fabrication over the disclosure made in the Clinton W. Stover Patent 1,463,601 as granted July 13, 1923.

The primary object of my improved method is to effectively and economically fabricate a perfectly sound chambered product 15 of this character, which will consistently be relatively flawless in metal structure especially as practiced by the drop-forged process where the action is impactive or percussive as 20 distinguished for instance from a more sustained pressure as applied in the case of a steam hammer or hydraulic press. The present method of making such insulator caps involves among other things, an improved 25 blanking operation preferably by the drop-forging method, that allows of working up a relatively large cup-shaped forging out of comparatively small bar-stock. Said operation also facilitates the shaping up of a uniform 30 skirt wall thickness and of otherwise holding the cap to exacting specifications, notwithstanding that the exterior of the cap dome is provided with a heavy integral suspension forming lug means forged to a thickness 35 considerably greater than that given the said skirt wall and which lug means preferably permits of completing the lug formation by machining surplus stock out of such solid dome metal.

40 The blank for making my cap is purposely carried through a series of different shapes prior to blocking out of the blank into a cup-shape, and one of such supplemental re-shaping steps includes a flattening operation designed to repeatedly work the blank central region and thus insure a more nearly 45 flawless swaging for the aforesaid thickened solid dome metal.

A further object is to provide in a drop 50 forging operation, means whereby the re-

quired expensive forging dies may afford longer life and to so carry out the steps of my method, that the various integral sections of my gang die block may all be made to wear out at an approximately uniform 55 rate rather than have any one such section of the needed costly dies, wear at a relatively faster rate and thus require the premature discarding of the entire gang block.

Die charges represent a considerable item 60 of expense in the forging of insulator caps, and I have found that because of the inherently limited intensity given to the series of rapidly repeated blows, the successful carrying out of the drop-forging process by the use 65 of board-lift hammers or the like, may be materially improved by a significant change in method over that heretofore practiced in connection with hydraulic or steam hammers, or the like where high pressure of 70 controllable intensity is gradually applied. An important advantage of the present adaptation to drop-forged purposes lies in greatly increasing the rate of fabrication obtainable from a given press and in correspondingly reducing the labor and other production costs to a level that will place the forged product upon a competitive price 75 basis with the more conventional caps of the cast malleable iron type.

To this end and the accomplishment of other new and useful results, my invention also consists in novel features of stock manipulation and die structure, all of which will hereinafter be more fully set forth.

Reference is had to the accompanying two sheets of drawings which are illustrative of a specific embodiment of my invention, particularly as applied to drop-forged insulator caps, in which drawings:

Fig. 1 is a sectional elevational view of an insulator cap assembly of the ear-suspension type.

Fig. 2 shows a perspective view of the billet or square bar stock from which a cap 95 may be forged.

Fig. 3 is a side elevation of a ram and die block members showing them brought into operative raised relationship.

Fig. 4 represents a top face view of the 100

lower compartmental die-block as seen from line 4—4 of Fig. 3, while Fig. 5 is a bottom face view of the companion top block as seen from the line 5—5 of Fig. 3.

5 Fig. 6 illustrates a sectional vertical view through the assembled blocks when brought into cooperative relationship as taken along the line 6—6 of Figs. 4 and 5.

10 Figs. 7, 8 and 9 are similar sectional block views as taken along line 7—7, 8—8, and 9—9 respectively.

15 Fig. 10 shows in perspective a roller type of impression that is initially shaped up in the first of my die compartments, while Fig. 11 is a perspective of the blank that is formed therefrom.

20 Fig. 12 represents a sectional perspective view of the forging as it comes from the blocker compartment of my die block, and Fig. 13 show said forging after it leaves the finishing compartment.

25 Fig. 14 illustrates a fragmental view of a modified or socketed dome type of cap which may be forged up in a substantially identical manner.

30 Fig. 15 is a cross-sectional view of the aforesaid impression as taken along line 15—15 of Fig. 10, while Fig. 16 is a similar view after such impression is flattened, as taken along line 16—16 of Fig. 11.

35 Referring now to Fig. 1, this shows one member adapted to make up a chain of petticoat insulator discs such as 10, of which the uppermost is ordinarily suspended in any suitable manner from a transmission tower or the like. The respective discs may be connected together in tandem by means of the interposed metal insulator caps such as 11, which cooperate with oppositely disposed 40 link-members such as 12, to constitute a built-up composite suspension insulator in the conventional fashion and of which the lowermost unit may be provided with a conductor clamp that carries the high tension 45 transmission wire (not shown).

50 My invention seeks to promote quality and uniformity of product and is more largely concerned with forging up said cap 11, which essentially comprises a flared tubular skirt portion 13 formed integrally with the dome portion 14. The dome shown in Fig. 1 is of the common clevis type affording a pair of spaced ears or straps such as 15 arranged to pivotally receive a clevis type of adapter link 55 12, although the particular mode of suspension is immaterial as far as the present purposes are concerned. The mouth region of my bell-shaped cap is generally cupped inwardly at 16 to constitute an undercut rim 60 for the reception of the disk neck or extension 17 which is intended to be securely cemented therein in the conventional manner.

65 Attention will now be directed to my improved die-blocks that are especially designed to facilitate the making of the desired cap

article. Figs. 3 to 9 inclusive illustrate a compartmental bottom die block 18 and a cooperating matrix or top die block 19 that is sunk in counter-part fashion. The respective die-blocks are here shown as equipped with four different compartments or mated recesses, of which the first may comprise a roller-like planchet forming chamber 20. The center region of this particular recess as measured from the die parting face preferably provides for a semi-cylindrical cavity with a cross-sectionally oval stem depression disposed at either end thereof as indicated. This die element is adapted to press up a distorted egg-shaped impression or planchet 21 (see Fig. 10) which may be formed up from the rectangular metal bar stock 22 that is shown in Fig. 2. The purpose of this initial step is to neck-in one end portion of the bar and gather sufficient stock in the overhanging bar extension to impart a transverse cross-sectional area to the body of said planchet (see Fig. 15) that shall become enlarged relative to the original bar stock, to the end that the body portion of the planchet 21 may be carried through a series of appropriate steps that admit of finally blocking out my blank into a flared skirted shape whose rim region shall be free from incipient flaws, cold-shuts in the ultimate product and without requiring the metal to be unduly strained during any one of the successive forging steps. The operative end of each die recess may be dished to provide for the usual sprue by which the hot forging is shifted into a different compartment.

55 As a second step, said planchet is subjected to a flattening action on the part of the blanking die compartment designated as 23 and which may comprise a relatively shallow central recess adapted to form up the pancake-like blank 24 preferably of spear-shaped contour. As represented in Figs. 11 and 16, the opposite side faces of this blank may be hollowed out somewhat between the pairs of marginal stiffening ridges such as 25. The described blank contour induces the forged metal to uniformly fill out the more distant die interspaces. The use of such ridge means is not however essential since the cited flattening action alone serves to more thoroughly work and thereby locally refine the metal lying in the centrally disposed body region of the initial impression or planchet 21; this metal portion ultimately forms up the thick dome wall element together with the supporting ears of my cap structure and all of which must be made capable of withstanding a heavy line load without rupture or incipient failure.

60 As a third step, said blank 24 after being flattened as described, is passed through the blocker compartment. The bottom die 18 thereof is preferably bored out at 27 for the snug insertion of a replaceable plug which

affords a rather blunt frustum-like protuberance 28 adapted to initially shape up the cap interior in cooperation with the corresponding top die recess 29. It will be observed that the diametral dimension "D" given to my blank 24 is preferably kept somewhat larger than the top face of the cone frustum 28 and that the flattened surface of such blank is preferably made to wholly overlap the perimeter of said top face. After the blank 24 has been blocked up, it assumes the impression designated as 30 in Fig. 12, from the dome exterior of which impression, there is extruded a potential ear forming lug whose shape includes a relatively narrow projecting boundary face having a trapezoidal profile.

Said impression is now passed through the finishing die compartment 31 which may also comprise a replaceable plug entered into the lower die-block 18 having a cone frustum tip 32. This tip is shown as not so bluntly shaped and adapted to cooperate with the corresponding depression in the top die 16 for the purpose of reforming the cap impression 30 into the semi-finished bell shape generally represented in Fig. 13 by the numeral 33 and in which shape, the potential ear lug perimeter may now be grooved or partially slotted 30 in order to reduce the heft of the metal where a milling cut is to be made by subsequently slotting the suspension lug into spaced complementary ears of the kind depicted in Fig. 1, it being preferred to forge a pair of rounded upstanding beads (see Fig. 13) between which to confine the said indented groove and thus avoid the need for grinding off burrs or otherwise finishing any sharp strap edges after said lug has been machine slotted. Up to this point, all of the described forging operations are intended to be carried out in a single heat and it will be observed that the dome portion 14 is forged rather heavy in comparison to the relatively thin and flared skirt walls 13.

It now remains to trim the flash and cause the rim region of the open mouth skirt to be crimped inwardly by any suitable die means. In addition, the thickened crown portion 50 may be machined or otherwise shaped up to provide for a pair of finished ears such as 15. Instead of the described clevis type of support, my cap may likewise be forged up and suitably machined to constitute a cap 55 34 of undercut socketed dome type such as illustrated in Fig. 14.

Having described my process in detail, further advantages accruing therefrom may be more fully pointed out. In the use of drop hammers operating with intermittent blows rather than sustained pressure, an undue number of repeated blows would be required if attempt were made to forge the bar stock directly into a thoroughly worked 60 product described in connection with fabri-

cating the blank 24. Such practice leads to excessive wear on part of certain compartments with the result that the remaining die recesses would at the same time become useless and soon require resinking or replacement by entirely new die equipment. It is further found that the plug elements 28 and 32 are likely to suffer from surface checks or even fracture, while with my improved design, it becomes possible to individually replace such plug elements 28 and 32 at a moderate cost. Said insertable plugs also allow of more readily changing the tip contour in order to hold the close tolerances that must be met in a product of this kind. Finally, the life of dies which do not include passing said egg-shaped planchet 21 through the blanking die compartment 23 according to my invention, has heretofore proven inadequate under such heavy-duty service and hardly likely to produce more than half the perfect impressions that can be obtained by the sequence of steps embodied in my improved method. The inclusion of the novel flattening step also tends to prevent the hot forging from sticking in the relatively deep die-recesses and at the same time reduces die charges in the making of complicated forgings of this kind.

It is to be understood that various changes in the structural details and mode of manipulation may be resorted to in carrying out my improved method of making insulator caps or like bell-shaped forgings, all without departing from the spirit and scope of my invention heretofore described and more particularly pointed out in the appended claims.

I claim:

1. The method of forging from bar stock, a one-piece supportable insulator cap of the undercut socketed type or the like, which method consists in swaging said stock into a relatively flat blank having an elongated contour provided with a depressed central face region flanked by spaced ridges, and thereupon blocking out said blank into a cup-shape comprising a skirt portion to which said ridges contribute stock, said skirt being provided with a mouthed rim end adapted to be subsequently cupped inwardly while the closed end of the cup is formed with a solid projection integral therewith.

2. The method of forging from bar stock, a one-piece supportable insulator cap of the undercut socketed type or the like, which method consists in gathering said stock into an egg-shaped planchet, then swaging said stock into a relatively flat blank having a spear-like contour, and thereupon blocking out said blank into a cup-shape comprising a relatively thick dome wall from which there is extruded an exteriorly disposed lug means for said cap.

3. The method of passing bar stock through compartmental die means and forging there-

from a one-piece supportable insulator cap or the like, which method consists in swaging said stock into successively different shapes starting with an egg-like shape and of which the last shape forms a relatively flat blank whose center region has been worked in a plurality of die compartments, and thereupon passing said blank into a different die compartment adapted to block out said blank 10 into cup-shape comprising a skirted portion of which one end is integrally closed by a dome wall portion to which the aforesaid center region contributes stock and which wall is shaped up to provide for an exteriorly 15 disposed supporting lug means for said cap.

4. The method of drop forging a one-piece cup-shaped member from bar-stock through the agency of compartmental die-block means, which method consists in working 20 said stock into successively different shapes by the use of a plurality of such die compartments and of which shapes the first comprises an egg-like shape and the last a flattened blank, and thereupon passing said blank into 25 still another compartment for the purpose of blocking out said blank into cup-shape, whereby to equalize the rate of die wear of all said die compartments.

5. The method of hot forging from bar-stock, in a single heat, a one-piece insulator cap or the like, which method includes an initial step of gathering stock to form a planchet of distorted egg-shape whose mid-transverse cross-sectional area is enlarged 35 over that of the original bar; thereupon, by the use of a separate supplementary swaging step, flattening a surface region of the aforesaid planchet; and by the use of still another step, blocking out such flattened planchet 40 into a cup-shape comprising a supportable dome portion to which said supplementary swaged metal contributes stock.

6. The method of forging from bar-stock, a one-piece insulator cap or the like, which 45 method includes an initial step of gathering stock to form a blank of distorted egg-like shape, the mid-transverse cross-sectional area of said shape being enlarged over that of the original bar; thereupon, by the use of a 50 supplementary swaging step, transforming said distorted shape to provide for a flattened blank having a surface of which the center region is slightly depressed; and by the use of still another step, blocking out such flattened blank into a cup-shape comprising a 55 supportable dome portion to which said supplementary swaged metal contributes stock.

7. The method of forging a one-piece insulator cap or the like from bar-stock by the 60 use of mated die-blocks having a blocking compartment therebetween, which method consists in gathering said stock into a distorted egglike shape, the mid-transverse area of said shape being enlarged over that of the original bar; and then by the use of a 65

supplementary swaging step, transforming said distorted shape to provide for a blank having a flattened surface region; and thereupon forming said blank into cup shape by means of the blocking compartment provided 70 with a chambered female block and a co-operating male block carrying a frustum-like projection that terminates in a blunt tip face, the aforesaid surface region being sufficiently flattened prior to blocking said blank 75 that when superimposed upon the tip face, said surface region will lie contiguous to, and overlap the entire perimeter of, the aforesaid tip face.

8. The method of forging from bar-stock, 80 a one-piece insulator cap or the like provided with machine slotted supporting ears, which method includes an initial step of gathering stock to form an impression of distorted egg-like shape, the mid-transverse 85 cross-sectional area of said shape being enlarged over that of the original bar; thereupon by a supplemental swaging step, transforming said distorted shape to provide for a flattened blank surface region that is centrally depressed and blocking out said flattened blank into cup-shape from the closed dome exterior of which there is extruded a solid, polyfaced ear-forming lug which includes a relatively narrow, projecting boundary-face of trapezoidal profile; and then by the use of still another step, finishing said cup-shape and simultaneously grooving a portion of the aforesaid boundary-face lengthwise thereof to facilitate the machine 90 slotting of said lug into spaced complementary supporting ears.

In testimony whereof, I have herewith set my hand this 9th day of May, 1930.

CHARLES S. CARD.
